UNITED STATES PATENT OFFICE.

HERMAN HARRISON, OF HARRISBURG, ILLINOIS.

LATCH.

1,170,252.

Specification of Letters Patent.

Patented Feb. 1, 1916.

Application filed June 25, 1913, Serial No. 775,775. Renewed December 1, 1915. Serial No. 64,583.

To all whom it may concern:

Be it known that I, HERMAN HARRISON, a citizen of the United States, residing at Harrisburg, in the county of Saline, State of Illinois, have invented certain new and useful Improvements in Latches; and I do hereby declare the following to be a full, clear, and exact description of the invention, such as will enable others skilled in the art 10 to which it appertains to make and use the same.

This invention relates to new and useful improvements in latches and has particular reference to spring pressed latches.

15 The object of the invention resides in the provision of a latch of the class described which will operatively engage the keeper when swung in relation thereto and which is provided with means for withdrawing the 20 latch bolt whereby a pull on said means will withdraw the latch bolt and open the gate in the same motion.

A further object is to simplify the general structure and improve the efficiency of 25 devices of this character.

With these and other objects in view, the invention resides in the novel combination, formation and arrangement of parts to be more fully described and illustrated in the 30 accompanying drawings and particularly pointed out in the claims hereto appended.

Reference is had to the accompanying drawings wherein similar characters of reference designate corresponding parts 35 throughout the several views, and in which:

Figure 1 is a side elevational view of the improved latch applied to a door and frame therefor, Fig. 2 is a sectional view on the line 2—2 of Fig. 1, Fig. 3 is a rear end elevation of the device, and Fig. 4 is a sectional view of the latch bolt showing means associated therewith for preventing its operative engagement with the keeper.

Referring now more particularly to the 45 drawings, there is shown a preferred form of the invention associated with the door 5 and frame 6. A latch bolt 7 is provided and disposed within a casing 8 which is secured to the door by means of U-clips 9 50 and 10 at its front and rear ends respectively. Disposed within the casing and surrounding the bolt is a coil spring 11, bearing at one end against a pin 12 passed through the outer end of the bolt to resili- 55 ently hold the bolt in a rearward position. This pin has its ends slidably disposed in

diametrically opposed longitudinal slots 13 to prevent rotation of the bolt with relation to its casing.

Secured to the frame 6 is a keeper 14 which comprises a plate having an outstanding arm 15. The top edge of this arm is beveled and the inner side edge of the arm is recessed to provide a shoulder 16. For engagement with this keeper the bolt 7 is extended outwardly of the casing and flattened to provide a head 17 and a longitudinal slot 18 is formed in said head. It is observed with reference to the drawings that when the door is swung to closed position the beveled portion of the keeper will draw the bolt forwardly so that it rides on the side edge of the arm 15. When the bolt reaches the recess it will move therein under the action of the spring 11 to lock the door 75 in closed position.

Means are provided for moving the latch bolt so that a pull on said means will actuate the latch bolt and in the same movement draw the door open. This means comprises 80 a lever 19 pivoted adjacent its rear end to a lug 20 formed on the bight portion of the U-clip 9. The rear end of this lever is provided with an inward extension, the lower end of which lies against the rear end of 85 the latch bolt 7, said rear end being extended past the casing. The forward end of the lever may be provided with a second inward extension 21 so that the longer end 22 of the lever serves as an efficient hand grip. 90 It will be now observed that by pulling on the grip portion the lever will be swung so that its inward extension 21 engages the rear end of the bolt and forces the said bolt forwardly so that the end of the slot 18 is 95 free of the shoulder 16. The latch being thus released the door moves to open position.

In order that there be no possibility of the door swinging closed and undesirably locking, a cap 24 is provided and adapted to fit over the head 17 of the bolt to cover the slot 18 to thus prevent its operative engagement with the keeper. This cap is preferably connected to one of the U-bolts 105 by a chain 25 or other flexible connection.

To provide means for withdrawing the latch from the inside, the pin 12 is extended through a slot 26 in the door and may be grasped to move the bolt.

What is claimed is:

1. A latch of the class described, compris-

- ing the combination with a door and a frame, of a casing secured to the door, a bolt disposed within the casing and having its ends extended therebeyond, a slotted head formed on the forward end of the bolt, a keeper having a beveled top edge and a shouldered side edge, a spring normally forcing the bolt to retracted position and a lever pivoted to move toward and away from the door having one end disposed adjacent the rear end of the bolt whereby pivotal movement of the lever will move the bolt forwardly.
2. A latch of the class described, comprising the combination with a door and a frame, of a casing, U-clips securing the casing to the door, a bolt disposed within the casing and having its ends extending therebeyond, a slotted head formed on the forward end of the bolt, a keeper on the frame having a beveled top edge and a

shouldered side edge, a spring normally forcing the bolt to retracted position, a lug extending from the bight of the rearmost U-clip, a lever pivoted to said lug, an inward extension on said lever engaging the rear end of the bolt. 25

3. A latch of the class described, comprising the combination with a door and frame, of a slidably mounted bolt, a spring for 30 forcing said bolt to retracted position, a slotted head formed on the forward end of the bolt, a keeper on the frame and having a beveled top edge and a shouldered side edge and a cap adapted to be disposed over 35 the head to cover the slot thereof.

In testimony whereof, I affix my signature, in the presence of two witnesses.

HERMAN HARRISON.
